CLAIM

The ornamental design for a headset for surgical system console as shown and described.

DESCRIPTION

FIG. 1 is a front elevation view of the headset for surgical system console showing our new design;

FIG. 2 is a left side elevation view;

FIG. 3 is a right side elevation view;

FIG. 4 is a top plan view;

FIG. 5 is a bottom plan view;

FIG. 6 is a perspective view;

FIG. 7 is another perspective view;

FIG. 8 is another front elevation view of the headset for surgical system console showing our new design;

FIG. 9 is a perspective view of FIG. 8; and,

FIG. 10 is another perspective view of FIG. 8.

Any broken lines in FIGS. 1 through 10 illustrate unclaimed portions of the headset for surgical system console and form no part of the claimed design.
